UNITED STATES PATENT OFFICE

DAVID C. PRINCE, OF SCHENECTADY, AND WILLIAM TURNPENNY, OF ALBANY, NEW YORK, ASSIGNORS TO GENERAL ELECTRIC COMPANY, A CORPORATION OF NEW YORK

HIGH TENSION CIRCUIT INTERRUPTER

Application filed May 19, 1931. Serial No. 538,560.

Our invention relates to high tension circuit interrupters, more particularly to multiple break interrupters of the oil blast type wherein pressure generating arcs are formed to cause flow of extinguishing liquid at high velocity through and across arcs in series in the circuit to be interrupted.

As is well known, the oil circuit breakers used in modern high tension power transmission systems, as for instance of 220 kilovolts, are massive, expensive, and require a large amount of space. The huge circuit breaker tanks on which the heavy lead-in insulating bushings are supported contain in most instances several thousand gallons of high grade insulating oil which is inflammable and a potential fire hazard so that a large factor of safety in the breaker design is necessary. Likewise powerful and expensive operating mechanisms are required to effect operation of the circuit breakers at the required speed. In brief, high tension oil circuit breakers in present use involve high initial, installation and maintenance costs and likewise involve the disadvantage of requiring a large amount of space and overhead clearance.

A principal object of our invention is the provision of an improved high tension circuit interrupter employing an arc extinguishing liquid, as oil, which shall be compact and of small mass, rugged and simple in construction, and positive and reliable in operation.

Our invention will be more fully set forth in the following description referring to the accompanying drawings, and the features of novelty which characterize our invention will be pointed out with particularity in the claims annexed to and forming a part of this specification.

Referring to the drawings, Fig. 1 is a partial cross-sectional, elevational view of a high tension circuit interrupter embodying our invention, Fig. 2 is a partial sectional plan view as viewed from beneath, and Fig. 3 is a cross sectional view taken along the line 3-3 of Fig. 1.

Referring to Fig. 1 of the drawings the high tension circuit interrupter comprises a generally tubular housing, horizontally ar-

ranged, formed by a pair of strong insulating tubes 1 and 2 joined by a flanged coupling member 3 which is in turn supported by the insulating shell 4. The insulating tubes 1 and 2 are preferably of laminated insulating material impregnated with a suitable resinous product forming a mechanically strong structure. For the purpose of convenience in illustration the part of the housing formed by the insulating tube 2 is but partially shown, it being understood that the insulating tube 2 and the structure associated therewith are similar to and substantially duplicate of that shown in connection with the insulating tube 1.

The terminals of the circuit interrupter comprise connecting means as the binding posts 5 and 6 extending through the end caps 7 and 8 suitably secured, as by screw-threaded engagement, to the opposite ends of the housing respectively. The circuit interconnecting the terminals 5 and 6 comprises a plurality of pairs of contacts connected in series by flexible conductors, certain pairs of contacts as 9-10 serving as pressure generating contacts and other contacts as 13-14 and 15-16 related thereto functioning to interrupt the circuit in a manner hereinafter described. In the present instance each half of the circuit breaker housing contains two pressure generating breaks, as 9-10 and 11-12, and four main current interrupting breaks, as 13-14, 15-16, 17-18 and 19-20, all connected in series and immersed in an insulating and arc extinguishing liquid, 21, as oil, contained in the housing, it of course being understood that the number and arrangement of breaks in series may be varied in accordance with the particular operating voltage and other considerations.

The contact operating mechanism comprises an operating rod 22 of strong insulating material, as wood, vertically movable within a tubular metallic guide 23 extending through and secured as by welding to a clamping plate 23' closing the upper end of the insulating shell 4. Suitable actuating means (not shown) disposed at the base of the insulating shell may be operatively connected to the rod 22 for imparting movement

thereto. For the purpose of opening the circuit interrupter at high speed independently of the actuating means, the rod 22 is connected through a link 24 to a rod 25 extending upwardly through a housing 26 mounted on the coupling 3 and terminating in a collar or the like 27 between which and the cap 28 on the housing 26 is disposed a compression spring 29 serving as an energy storing device for causing circuit opening movement. Motion is transmitted from the operating rod 22 to the switch contacts through a crank 30 pivoted to the coupling 3 as at 31. An arm 32 of the crank extends through a slot 22' in the guide tube 23 and is pivotally connected to the rod 22. Another forked arm 33 of the crank engages a cross pin 34 interconnecting a pair of parallel contact operating rods 35 and 36 of strong insulating material, as maple, extending horizontally within the breaker housing so as to cause reciprocatory movement of said rods in response to rotation of the crank.

Referring more particularly to Fig. 2, the parallel rods 35 and 36 serve to guide and actuate the movable contacts 10 and 12 of the pressure generating contacts, and 14, 16, 18 and 20 of the main current interrupting contacts, and likewise the corresponding movable contacts disposed within the insulating tube 2. Each movable contact is connected to a crossbar 37 mounted for sliding movement on the rods 35 and 36, the crossbar and likewise the movable contact being normally biased towards closed circuit position by the coil springs 38 disposed between the crossbar 37 and the insulating sleeves 39 which are pinned or otherwise secured to the rods 35 and 36. For the purpose of moving the crossbars in the opposite direction the insulating sleeves are of suitable length to engage and move the crossbar of the adjacent contacts.

The main mounting and supporting structure for the contacts and for the rods 35 and 36 comprises a strong insulating partition 40 of laminated wood or the like disposed within the housing as best illustrated in Fig. 3, forming a lower pressure generating chamber and an upper relief chamber, the partition 40 being suitably positioned and braced by the bolts 41 and insulating spacing blocks 42 disposed at opposite ends of the housing. The mid-portion of the partition 40 is likewise supported and braced by a plate 40' which is secured as by welding to the coupling 3, the guide tube 23 extending freely through the partition 40 and plate 40'. The crank 30 fits snugly within a slot 30' formed in the partition 40 so that communication between the upper and lower chambers is restricted except as hereinafter described.

Opposite the main current interrupting contacts in the partition 40 are pressure relief openings 43, 44, 45 and 46, each pair of

contacts being positioned within an insulating tube or thimble 47, open at both ends, secured in any suitable manner within the corresponding relief opening to the partition 40 as by threaded engagement with a retaining insulating washer 48. As clearly illustrated in Fig. 1 the oil level is but a short distance above the partition 40 and the relief openings, thereby maintaining a low pressure head at those points. 70 75

Each pair of the main current interrupting contacts is similar in arrangement, the stationary contact 13 of the break 13-14 for example extending through and clamped to the wall of the corresponding thimble 47 by suitable means 49 serving likewise to connect one end of a flexible braided conductor 50 to the stationary contact. The coacting movable contact 14 which is carried by a crossbar 37 extends through and is slidably mounted and supported within the opposite wall of the thimble so as to make and break contact within the thimble and adjacent the relief opening 43. The remaining main current interrupting contacts are similarly mounted within thimbles 47 so that further description thereof is unnecessary. 80 85 90

The pressure generating contacts on the other hand are remotely positioned from the relief openings in the partition 40 and are preferably placed intermediate a pair of main interrupting contacts. Referring by way of example to the pressure generating contacts 9 and 10, the stationary contact 9 is suitably secured to one arm of a U-shaped member 51 clamped to the lower side of the partition 40 by a bolt 41, the U-shaped member likewise supporting and guiding the movable contact 16 of the adjacent pair of main contacts. The movable contact 10 is carried by crossbar 37 in a manner above described and is controlled by movement of the rods 35 and 36. The pressure generating contacts 11 and 12 are similarly arranged and constructed. 95 100 105 110

The pairs of contacts, both pressure generating and main current interrupting, are all connected in series by the flexible braided conductors 50 connecting a movable contact of one pair with the stationary contact of the next pair in series therewith. A braided conductor 52 likewise connects the sets of contacts on opposite sides of the housing in series through the coupling 3, the contacts being connected to the terminals 5 and 6 by the conductors 53 and 54 respectively. 115 120

For the purpose of venting gas from the upper relief chamber and for preventing expulsion of oil therefrom, the housing 26 forms a separating chamber of the well known pebble type, the chamber having a lower perforated wall 55 supporting a body of pebbles, 56. The cap 28 is likewise perforated as at 57 so that gas may be freely vented 125 130

through the separating chamber while preventing expulsion of oil therefrom.

In actual practice a grading resistance (not shown) may be connected in parallel across the terminals, taps from the resistance being suitably connected across the individual pairs of main current interrupting contacts for the purpose of equalizing the voltage at each pair of contacts. This arrangement, however, forms no part of our present invention and has been omitted for the purpose of clarity since illustration thereof is not necessary for complete understanding of our invention.

15 The operation of the circuit interrupter is as follows: When the circuit interrupter is in the closed circuit position illustrated in Fig. 1 wherein each pair of contacts is in engagement, the spring 29 is under compression tending to rotate the crank 30 in a counter-clockwise direction to cause opening movement of the parallel rods 35 and 36. When the operating rod 23 is released by tripping mechanism of any suitable type 20 either at the option of the operator or in response to a predetermined abnormal condition in the circuit of the interrupter, the compression spring 29 forces the rod 25 upwardly shifting the parallel rods 35 and 36 25 by the crank 30 towards the right or open circuit position and causing substantially simultaneous separation of each pair of contacts. When this occurs it will be noted that the pressure generating contacts 9, 10 30 and 11, 12 are so located in the lower compartment of the housing that the arcs drawn by these contacts generate, as is well known, high pressure in that region. The main current interrupting contacts however are so 35 arranged with respect to the respective relief openings that the arcs drawn between the same are directly in the path of flow of oil exhausting into the upper relief chamber. By positioning a pair of pressure generating 40 contacts between a pair of main current interrupting contacts, sufficient pressure is generated within the lower pressure chamber to cause a blast of oil at high velocity upwardly 45 through each of the thimbles and associated relief opening so that the arc drawn within the thimble by the corresponding main contacts is traversed and effectively extinguished by the oil blast in exhausting into the upper 50 relief chamber which may be at atmospheric 55 pressure. In view of the fact that all main current interrupting contacts are in series and are opened practically simultaneously, the arc at each pair of main contacts is traversed simultaneously by an oil blast so that interruption of the circuit is positive and effective. Furthermore, the arcs formed within the thimbles 47 have no chance to shift from or dodge the oil blast since the entire arc 60 space is subjected to the blast of oil.

65 The switch closing operation is effected

simply by downward movement of the operating rod 22 by the actuating means, causing clockwise movement of the crank 30 to shift the parallel rods 35 and 36 to the circuit closing position, meanwhile compressing the spring 29 for a subsequent circuit opening 70 operation. The springs 38 which normally bias the crossbars 37 and the movable contacts towards closed circuit position serve to resiliently bias the contacts into engagement 75 as well as provide for overtravel of the operating mechanism during the closing operation, the insulating sleeves 39 engaging the bars 37 in the circuit opening operation.

The operation of a high tension circuit interrupter embodying our invention is without appreciable noise and is accompanied by low gas pressure and very little, if any, oil throw, thereby reducing to an appreciable extent fire hazard. The circuit interrupter moreover for a given interrupting rating is small and occupies little space and requires but a few gallons of oil as compared with the huge amount required by oil circuit breakers now in use. Furthermore, the operating mechanism may be simple and have a comparatively 80 low power rating.

Although oil is specifically referred to as the insulating and arc extinguishing liquid, it should be understood that other insulating and extinguishing liquids having suitable characteristics may be used. Oil, however, has the advantage of being a lubricant as well so that all moving parts are sufficiently lubricated at all times.

Under certain conditions, as in outdoor operation, an outer insulating shell of porcelain or the like may be used to substantially enclose the elongated tubular housing, thereby minimizing the chance of flashover between 85 live parts of the breaker.

It should be understood that our invention is not limited to specific details of construction and arrangement thereof herein illustrated, and that changes and modifications 90 may occur to one skilled in the art without departing from the spirit of our invention.

What we claim as new and desire to secure by Letters Patent of the United States, is:

1. A high tension circuit interrupter comprising a housing having a pressure chamber and a relief chamber communicating therewith through a plurality of relief openings, an arc-extinguishing liquid filling said pressure chamber, and a plurality of pairs of contacts connected in series in said pressure chamber, certain pairs of said contacts being adjacent and opposite said relief openings and other pairs of contacts being remotely positioned with respect to said relief openings whereby the arcs drawn between said remotely positioned contacts generate pressure within the pressure chamber causing blasts of extinguishing liquid through said relief open-

ings and across the arcs drawn between the corresponding adjacent pair of contacts.

2. A high tension circuit interrupter comprising a housing having a lower pressure chamber and an upper relief chamber connecting through a plurality of relief openings, an insulating and arc-extinguishing liquid filling said lower chamber, a plurality of pairs of contacts connected in series immersed in said liquid, certain of said pairs of contacts positioned adjacent and opposite said relief openings and other of said pairs of contacts being remotely positioned with respect to said openings, and means operatively connected to said pairs of contacts causing simultaneous separation thereof so that the arcs drawn between said remotely positioned contacts generate pressure within the pressure chamber to blast extinguishing liquid through said relief openings and across the arcs formed between the corresponding adjacent pair of contacts.

3. A high tension circuit interrupter comprising an elongated tubular housing horizontally arranged, a partition in said housing forming a lower pressure chamber and an upper relief chamber, said chambers communicating through relief openings in said partition, an arc-extinguishing liquid filling said pressure chamber, a plurality of pairs of contacts connected in series immersed in said liquid within the pressure chamber, certain of said pairs of contacts disposed adjacent and opposite said relief openings and other of said pairs of contacts remotely positioned with respect to said openings, means guiding the exhaust of liquid from said pressure chamber through each relief opening so that the corresponding pair of adjacent contacts is directly in the path of said liquid, and means operatively connected to each pair of contacts causing simultaneous separation thereof so that the remotely positioned contacts form pressure generating breaks for forcing extinguishing liquid at high velocity through said relief openings and across the arcs formed between the corresponding adjacent contacts.

4. A high tension circuit interrupter comprising an elongated insulating housing horizontally arranged, an insulating partition dividing said housing into a lower pressure chamber and an upper relief chamber, said chambers communicating through relief openings in said partition, an insulating and arc-extinguishing liquid filling said pressure chamber, a plurality of pairs of contacts connected in series immersed in said liquid within the pressure chamber, insulating thimbles mounted in said relief openings and extending into said pressure chamber, certain of said pairs of contacts each arranged to make and break contact within a corresponding thimble and adjacent its relief opening, other pairs of said contacts being remotely

positioned with respect to said relief openings, and contact operating means causing substantially simultaneous separation of each pair of contacts so that the pressure generated by arcing between the remotely positioned contacts serves to force extinguishing liquid at high velocity from said pressure chamber through said insulating thimbles to extinguish the arcs formed therein.

5. A high tension circuit interrupter comprising a housing having a partition dividing the same into a lower pressure chamber and an upper relief chamber, said chambers communicating through relief openings in said partition, a plurality of pairs of contacts connected in series within said pressure chamber, an insulating liquid in said chamber in which said contacts are immersed, certain of said pairs of contacts serving as main current interrupting contacts positioned adjacent and opposite said relief openings, another pair of said contacts serving as pressure generating contacts positioned intermediate two pairs of main current interrupting contacts, and contact operating means effecting separation of each pair of contacts so that arcing at the pressure generating contacts forces insulating liquid at high velocity between said main current interrupting contacts to exhaust into said relief chamber.

6. A high tension circuit interrupter comprising an insulating tubular housing horizontally arranged, an insulating partition dividing said housing into a lower pressure chamber and an upper relief chamber, said chambers communicating through relief openings in said partition, an insulating oil within said pressure chamber, a plurality of pairs of contacts connected in series within said pressure chamber, said contacts mounted on and supported by said partition, certain pairs of said contacts positioned adjacent and opposite said relief openings, and operating means causing substantially simultaneous separation of each pair of contacts so that the arcing pressure generated by the contacts remotely positioned with respect to said relief openings forces individual blasts of oil through the relief openings and across the arcs formed thereat.

In witness whereof we have hereunto set our hands.

DAVID C. PRINCE.
WILLIAM TURNPENNY.
